UNITED STATES PATENT OFFICE.

SAMUEL J. KELSO, OF DETROIT, MICHIGAN.

SLIP-HOLDER.

SPECIFICATION forming part of Letters Patent No. 477,942, dated June 28, 1892.

Application filed November 10, 1891. Serial No. 411,459. (No model.)

To all whom it may concern:

Be it known that I, SAMUEL J. KELSO, of Detroit, in the county of Wayne and State of Michigan, have invented a new and Improved 5 Slip-Holder, of which the following is a full, clear, and exact description.

My invention relates to improvements in a device adapted to hold salesmen's entry-slips and similar articles; and the object of my invention is to produce a holder which may be conveniently carried about, which will hold a quantity of entry-slips, bills, or any other analogous articles, so that they will not be scattered about, and which will also hold them 15 in a manner to be easily written upon either when the holder is held in the hand or laid upon a support.

To this end my invention consists of certain features of construction and combinations of parts, which will be hereinafter described and claimed.

Reference is to be had to the accompanying drawings, forming a part of this specification, in which similar figures of reference indicate 25 corresponding parts in all the views.

Figure 1 is a plan view of the holder embodying my invention with entry-slips in place therein. Fig. 2 is a cross-section on the line $\alpha\alpha$ in Fig. 1. Fig. 3 is a plan view of the 30 case and tablet when removed from the holder proper, and Fig. 4 is a longitudinal section of the entire device.

The device is provided with a rectangular case 10, which is open on the top side and 35 which is recessed at one end, as shown at 11, which recess is for the purpose of enabling the entry-slips or other articles to be conveniently pulled from off the tablet 12, which tablet fits loosely in the case 10 and is provided 40 with posts 13, which extend downward to the bottom of the case 10 and which serve as guides for the tablet, and which also enable it to be rigidly supported when the device is placed upon a support, so as to stand upon 45 the posts. The tablet 12 is also provided with side pins 15, which extend outward through slots 16 in the sides of the case 10, and which also project through similar slots 17 in the sides of the holder proper which carries the 50 case, and which will be described below. The tablet 12 is pressed to the upper portion of the case 10 by a curved flat spring 18, which is

centrally secured to the under side of the tablet, as shown at 19 in Figs. 2 and 4, and the free ends of which rest upon the floor of the 55 case 10; but it will be understood that any otherspring may be substituted for this spring with like effect. The case 10 is held in a holder 20, which holder is also of a rectangular shape and corresponds in length to the 60 length of the case 10, and the holder is open at each end, so that the case may be conveniently slipped into it or removed from it. The holder 20 is provided on opposite sides and at top and bottom with flanges 21, which are 65 thus adapted to overlap the top and bottom portions of the case 10 and which form a slide-way into which the case may be pushed. The holder 20 has also at the top and at one end a top plate 22, in which are openings 23, the 70 object of which is to enable the numbers or other marks upon an entry-slip or similar article to be observed. The top flanges 21 of the holder 20 are also connected by a cross-piece 24, which is arranged at a little distance 75 from the top plate 22 and parallel therewith, thus forming a slot 25, which is large enough to permit the name of a transaction to be recorded or any other writing to be produced upon the slip. The entry-slips or other similar articles are carried upon the tablet 12, and the pressure of the spring 18 forces the tablet upward and presses the slips against the cross-piece 24 and top plate 22, and it will be seen 80 that the cross-piece and top plate, in connection with the tablet, also serve the purpose of a clamp, which enables the slips to be held firmly in place.

The operation is as follows: A quantity of the slips 26 are placed upon the tablet 12 and 90 the tablet is pushed downward into the case 10 and the case thrust into the holder 20. The slips 26 will thus be in position for use, and the salesman or other person using them may hold the device in his hand while he writes the name of the transaction upon the slip and within the slot 25 and fills in any other necessary matter upon the lower portion of the slip. The slip may then be withdrawn by pressing downward upon the tablet, and this 95 operation is facilitated by means of the pins 15, as the operator may with his fingers push downward upon the pins. The pins 15 are 100 not absolutely necessary, although they fa-

cilitate the usual operation of the device, as where the pins are not used the operator may press downward with his thumb upon the slips 26 and tablet 12, thus pushing the tablet downward and permitting the withdrawal of the slip. It will be noticed that the tablet is normally pressed upward, so that after a slip is withdrawn the remaining slips will be held firmly in place, and consequently the slips cannot be scattered about.

Having thus fully described my invention, I claim as new and desire to secure by Letters Patent—

1. A slip-holder comprising an open-top case adapted to receive the slips and having a spring-pressed follower to press the slips outward, and a holder into which the case is passed and provided with flanges overlapping the longitudinal edges of the sides of the said case, substantially as set forth.

2. A slip-holder comprising a case having slots in its sides and open at its top and a spring-pressed follower or tablet in the case and having pins projecting through the said slots, substantially as set forth.

3. A device of the character described, comprising an open-topped case, a spring-pressed tablet mounted in the case and having guide-posts extending through the case-bottom, and a holder for the case, said holder having cross-

strips extending across the case-top, substantially as described.

4. A device of the character described, comprising an open-topped case having one end cut away or recessed, a spring-pressed tablet 35 mounted in the case, and a holder for the case, said holder having cross-strips extending across the case-top, substantially as described.

5. A device of the character described, comprising an open-topped case, a spring-pressed 40 tablet mounted in the case and having posts extending through the case-bottom, a holder for the case, having cross-strips extending across the case-top, and pins secured to the sides of the case and extending outward 45 through slots in the case and holder, substantially as described.

6. A device of the character described, comprising an open-topped case, a spring-pressed tablet mounted therein, and a holder for the 50 case, said holder having side flanges to embrace the top and bottom of the case and having cross-strips extending across the case, one of said cross-strips having openings therein, substantially as described.
